UNITED STATES PATENT OFFICE.

RAYMOND FISHER, OF PHILADELPHIA, PENNSYLVANIA.

KNITTING-MACHINE.

1,285,096.

Specification of Letters Patent. Patented Nov. 19, 1918.

Application filed October 5, 1914. Serial No. 865,020.

To all whom it may concern:

Be it known that I, RAYMOND FISHER, a citizen of the United States, residing at Philadelphia, in the State of Pennsylvania, 5 have invented a certain new and useful Improvement in Knitting-Machines, whereof the following is a specification, reference being had to the accompanying drawings.

My invention may be employed in connection with any tubular knitting machine and is designed to automatically sever the knit tube at intervals, which may be variably predetermined by setting a suitable pattern mechanism, without the interposition of the 15 operator, if desired, or at intervals arbitrarily determined by the operator, independently of such pattern mechanism. For instance, my invention is applicable to an automatic hosiery machine to sever the primarily continuous tubular product of such a machine into individual and uniform hose lengths, so that the product of such a machine equipped with my invention is a series 20 of independent individual hose lengths instead of a continuous tube.

Heretofore, it has been customary, and in fact necessary, to discharge the product of such an automatic hosiery machine as a continuous tube, and subsequently manually 30 sever it to form individual hose lengths, such severing operation not only necessitating the repeated handling of the product but causing a lack of uniformity in the lengths of the successive severed portions of the hose 35 tube due to the inevitable inaccuracy of rapid manual severing operations. Moreover, as it is practically impossible to manually cut such a loose tubular product in the lines of the knit courses, in view of the 40 speed at which such manual operation must be performed to be commercially practical, there is a consequent waste of a considerable percentage of the length of the tube at each place where it is severed, for instance, one- 45 half inch or more of the tube may be wasted at each junction of the successive hose patterns by inadvertently cutting the courses diagonally.

Therefore, my invention is advantageous 50 in that it not only saves the cost of handling a continuous tube to sever it into hose lengths, but also prevents the waste of material and time incident to the manual operation aforesaid. Moreover, all of the hose lengths being 55 predetermined to be uniform, the time here-

tofore wasted in pairing the individual hose, necessitated by the variable lengths thereof produced by inaccurate cutting, is saved.

I have found it convenient to illustrate 60 my invention in connection with "the Banner full automatic hosiery machine" wherein the needle cylinder is rotary and controlled by a pattern chain which is utilized to initiate and terminate the operation of my device 65 as applied to that machine. However, it is to be understood that I do not desire to limit myself to such an embodiment of my invention.

My invention includes the various novel 70 features of construction and arrangement hereinafter more definitely specified.

In the drawings; Figure I is a fragmentary sectional elevation of a full automatic hosiery machine, with an embodiment of my 75 invention adapted to be controlled by the pattern chain of said machine, and including a special shear cam on the pattern shaft.

Fig. II is a fragmentary plan view of 80 said machine showing my device illustrated in Fig. I.

Fig. III is a fragmentary vertical sectional view showing the shear roller and shear track elements of the form of my invention shown in Figs. I and II. 85

Fig. IV is a fragmentary plan view of such a full automatic hosiery machine as shown in Figs. I and II with a modified form of my invention applied thereto.

Fig. V is a fragmentary vertical sectional 90 view showing a shear roller and shear track elements of the form of my invention shown in Fig. IV.

In said figures I have shown only so much of the ordinary elements of the full automatic hosiery machine as are necessary to illustrate the application of my invention to that machine, including the rotary needle cylinder 1 provided with needles 2 arranged to be operated by the cam cylinder 3 which is 95 stationary on the machine frame 4. The main shaft 5 has, fast at its inner end, the bevel gear 6, engaging the bevel gear 7 on the lower end of said needle cylinder 1, and said shaft 5 is provided with means, of ordinary construction, to rotate it continuously or oscillate it. The form of my invention herein described is only operative when said shaft 5 is continuously rotated. 100

Said machine includes, as ordinary ele- 110

ments thereof, the pattern shaft 10 on which is loosely mounted the chain ratchet wheel 11 carrying the pattern chain 12. Said pattern wheel 11 is rotated, step by step, by the 5 pawl 14 which successively engages the teeth 15 thereof and is oscillated in definite relation to the movement of the needle cylinder, regardless of whether the latter is being continuously rotated or oscillated, so that 10 said chain 12 is shifted, in the direction of the arrow marked thereon, in definite relation to the movement of said needle cylinder. Said pattern shaft 10, which extends loosely through said chain ratchet wheel 11, 15 is rotated, step by step, by another pawl 17, similar to said pawl 14 and oscillated synchronously therewith but said pawl 17 is normally upheld in the idle position shown in Fig. I, by the oscillatory pawl holder 18 which is so weighted that it normally hangs 20 in the position shown, but has the projection 19 adapted to be encountered by the high links on said chain 12 which swing said pawl holder 18 to the right, with reference 25 to Fig. I, and thus permit the cam pawl 17 to operate it.

Said machine is constructed and arranged, for instance as set forth in my copending application Serial No. 849,020 for Letters 30 Patent of the United States, to knit a stocking tube of a pattern including a toe pocket, a foot, a heel pocket, and a leg, represented by respective sections of said chain, but the present invention is operative only during 35 those periods of the cycle of operation of the machine when continuous circular courses are being knit, between successive toe pockets and legs. Ordinarily such courses are knit in zones approximately two inches in 40 length to allow for irregularities in cutting the tube thereat, and the greater portion of such zones is wasted. My invention permits such zones to be made much narrower than heretofore, thus saving a considerable proportion 45 of the thread heretofore wasted. Moreover, I prefer to make the central portion of such intermediate zones of several courses of weak thread, to not only save the cost of the more expensive stronger thread 50 but facilitate the severing operation of my invention.

The several threads employed in knitting the hosiery tube 24 are shifted to and from operative relation with the needles 2 by 55 five thread guide levers 25, 26, 27, 28 and 29 of which 25 carries the double thread employed in knitting the toe pockets and 29 carries the thread employed in knitting the zones where the tube is to be severed. Said 60 guides are provided with respective springs 30, indicated in Fig. II, tending to lower them into operative relation with the needles, but said levers are independently operated by respective rods 32 connected with respective drum levers 33 fulcrumed at

34 in said frame 4 and arranged to be shifted by respective thread guide cams 35 fixed on the pattern shaft 10. To effect the operation of said thread guide levers 25 and 29 at the proper intervals in the sequence 70 of operation of said machine, the pattern chain 12 is provided with the high link 37 which causes the double toe thread to be thrown out of operation; the low link 38, which causes the weak thread to be thrown 75 into operation; and the low link 39, which causes said weak thread to be thrown out of operation. Said chain also includes the link 40 having a high portion of such length as to maintain the mechanism in position for the 80 severing operation throughout four revolutions of the needle cylinder.

The mechanism which directly effects the severing operation includes the special shear cam 42 on said pattern shaft 10, arranged to operate a lever 43 which is fulcrumed at 45 on said frame 4 and has its opposite end pivotally connected at 46 with the rod 47 which has its upper end pivotally connected at 48 with the lever 49 which is fulcrumed at 50 on said frame 4 and has its opposite end pivotally connected at 52 with the slide rod 53 which is mounted to slide through the bearing 55 and has its upper end pivotally connected at 56 with the shear lever 57 95 which is fulcrumed at 58 on the bracket 59 of the latch ring carrying the thread guide levers. Said lever 57 carries at its inner end the shear roller 60, in coöperative relation with the stationary circular track 61. Said track 61 has four standards 62 fitting said needle cylinder 1 and secured by the screws 51 at the bottom thereof, as shown in Fig. I, so that said track 61 is held in fixed relation to the needle cylinder within said series of needles 2, in such position that said tubular knit fabric 24 extends between said track 61 and said roller 60 as shown in Fig. III, and said track is rotated by and with said needle cylinder so as to cause said roller 60 to traverse 100 said track in the position shown in Fig. III when it is desired to sever said fabric. 105

It is to be understood that the construction and arrangement is such that said roller is lowered into the coöperative position with 110 respect to the track, to sever the fabric 24 at the zones of weak thread in the latter. It may be observed that although the contiguous surfaces of said roller 60 and track 61 are beveled to fit each other, so that said roller is rotated by frictional engagement with said track, (or the knit fabric on it) their angular relation to the axes of said roller and track is such as to cause slip of 115 said surfaces as they relatively move, so that although said roller 60 is blunt edged the severance of the fabric is effected, though 120 by a grinding rather than a cutting operation. Such shearing mechanism is advantageous 125 in that there is no cutting edge re- 130

quiring to be maintained in operative condition.

The spring 63 extending from the pin 64 on said slide rod 53 to the pin 65 on the frame 4 presses said rod 53 in the direction opposite to that indicated by the arrows shown in Fig. I, so as to press the right hand end of the lever 43 toward the cam 42 and insure that the roller 60 is instantly 5 lifted and upheld by said spring 63 when said cam 42 passes from under said end of the lever 43. Said construction is such that the extent of the movement of said roller 60 toward its track 61 is determined by the 10 radial extent of said cam 42. However, said roller 60 is carried on the lever 57 by the hanger 66 which is normally rigidly connected therewith by the set screw 67 extending 15 through the slot in said hanger so that the latter may be adjusted to precisely determine the position of said roller 60 when said cam 42 is operatively engaged with said lever 43, and thus determine the degree of pressure of impact of said roller 60 on said 20 track 61 in accordance with the nature and thickness of the fabric 24 to be severed; so that the severing operation may be effected with the minimum amount of pressure and friction upon the mechanism.

It is to be understood that the lever 57 is provided with the slot 69 for engagement with the pivotal connection 56 at the upper end of the slide rod 53 in order to permit the bracket 59, carrying the thread guide 25 levers and shearing mechanism above described, to be turned upwardly upon its pivot 70 in the frame 4 so as to afford free access to the needle cylinder, and release the sinker head cap 71, the movement of which 30 is normally restricted by said bracket 59 extending between the set screws 72 on said cap. In other words such specific construction of the lever 57 is merely incidental to its embodiment in the particular type of 35 knitting machine chosen for illustration.

However, it is to be understood that I do not desire to limit myself to the form of my invention above described embodying the dull edged shearing roller 60 coöperating 40 with the track 61, as with some classes of fabric I prefer to employ a shearing roller with a cutting edge arranged to coöperate with a track also having a cutting edge. For instance, as shown in Figs. IV and V, 45 the shear track 75 having the cutting edge 76, is substituted for said track 61; said track 75 having the standards 78, similar to the standards 62 on said track 61, for engagement with the needle cylinder, as shown 50 in Fig. I. Said track 75 is traversed by the shearing roller 80 having a cylindrical portion opposed to the upper plane surface of said track 75 and having the cutting edge 81 maintained in shearing relation with the 55 cutting edge 76 of said track. Said shear-

ing roller 80 is journaled upon the stud 82 projecting from the hanger 83 which is operatively connected with and carried by the lever 57, like the hanger 66 above described, and said roller cutting edge 81 is conveniently maintained in shearing relation with said track cutting edge 76 by the spring 85, shown in Fig. IV, secured to the bracket 59 by the screw 86 and having its free end bearing upon said lever 57. Of course, said roller 80 and said plane surface of the track 75, upon which it bears, should be beveled if it is desired to avoid any slip in their relative movement. However, I find said two elements coöperate satisfactorily when 60 formed as shown in Fig. V, regardless of the relative slip of said elements incident to their form shown.

Moreover, although in both forms of my invention shown and described the operation 65 of the fabric severing mechanism is initiated and terminated by the pattern chain 12; such control is incidental to the particular construction and arrangement of the machine illustrated, and may be otherwise effected. For instance, I may employ a pattern element such as the shear cam 42, and the parts between it and the shear lever 57 to control the latter, without necessarily 70 controlling said shear cam 42 by the pattern chain 12 and intermediate mechanism, indicated in Fig. I, which is of the specific construction shown in my copending application Serial No. 849,020; or I may employ a track 61 and roller 60 without necessarily 75 controlling the movement of the latter by the construction and arrangement above described, connecting the lever 43 with the lever 57. Therefore, I do not desire to limit myself to the precise construction and arrangement herein set forth, as it is obvious 80 that various modifications may be made therein without departing from my invention as defined in the appended claims.

I claim:

1. In a full automatic circular knitting machine provided with a revoluble annular needle cylinder; mechanism for cutting off predetermined lengths of fabric; including a circular track within the needle cylinder, having an annular face extending transversely to the axis of said cylinder; a shearing roller arranged to traverse said annular track face and having its axis extending transversely to the axis of said needle 110 cylinder and track; and means arranged to automatically move said shearing roller to and from cutting position in relation to said track; thread changing mechanism arranged to produce zones of weak thread at predetermined uniform intervals in the length of the fabric knit by said machine; and pattern mechanism arranged to coöperatively control the knitting and shearing operations of said machine; whereby said shearing mech- 115 120 125 130

anism is rendered operative only when a zone of weak thread is in registry with said track.

2. In a circular knitting machine, the combination with a series of needles; of thread changing mechanism arranged to produce a tubular knit fabric with successive zones of weak thread at predetermined uniform intervals in the length of said fabric; a circular track within said series of needles; a shear roller arranged to traverse said track, in coöperative shearing relation therewith; said roller having its axis extending transversely to the axis of said track; means arranged to automatically move said shearing roller to and from cutting position in relation to said track; and pattern mechanism arranged to coöperatively control the knitting and shearing operations of said machine; whereby said shearing mechanism is rendered operative only when a zone of weak thread is in registry with said track.

3. In a circular knitting machine, the combination with a series of needles; of thread

changing mechanism arranged to produce a tubular knit fabric with successive zones of weak thread at predetermined uniform intervals in the length of said fabric; a circular track within said series of needles; a shear roller arranged to traverse said track, in coöperative shearing relation therewith; means arranged to automatically move said shearing roller to and from cutting position in relation to said track; and pattern mechanism arranged to coöperatively control the knitting and shearing operations of said machine; whereby said shearing mechanism is rendered operative only when a zone of weak thread is in registry with said track.

In testimony whereof, I have hereunto signed my name at Philadelphia, Pennsylvania, this twenty-fourth day of September, 1914.

RAYMOND FISHER.
